(57) **CLAIM**

The ornamental design for a facial brush with brush head cover, as shown and described.

DESCRIPTION

FIG. 1 is a perspective view of a facial brush with brush head cover disposed within an exemplary base in accordance with the present invention;

FIG. 2 is an elevational front view of the facial brush with brush head cover and base of FIG. 1;

FIG. 3 is an elevational rear view of the facial brush with brush head cover and base of FIG. 1;

FIG. 4 is a top plan view of the facial brush with brush head cover and base of FIG. 1;

FIG. 5 is a bottom plan view of the facial brush with brush head cover and base of FIG. 1;

FIG. 6 is an elevational front view of the facial brush with brush head cover of FIG. 1 uncoupled with the base of FIG. 1 in accordance with the present invention shown separately for clarity of illustration;

FIG. 7 is an elevational rear view of the facial brush with brush head cover of FIG. 6 uncoupled with the base in accordance with the present invention shown separately for clarity of illustration;

FIG. 8 is an elevational left side view of the facial brush of FIG. 6 uncoupled with the base in accordance with the present invention shown separately for clarity of illustration;

FIG. 9 is an elevational right side view of the facial brush of FIG. 6 uncoupled with the base in accordance with the present invention shown separately for clarity of illustration;

FIG. 10 is a perspective view of the facial brush of FIG. 6 uncoupled with the base in accordance with the present invention shown separately for clarity of illustration;

FIG. 11 is a top plan view of the facial brush of FIG. 6 uncoupled with the base in accordance with the present invention shown separately for clarity of illustration;

FIG. 12 is a bottom plan view of the facial brush of FIG. 6 uncoupled with the base in accordance with the present invention shown separately for clarity of illustration;

FIG. 13 is an elevational front view of the exemplary base of FIG. 1 uncoupled with the facial brush of FIG. 1 in accordance with the present invention shown separately for clarity of illustration;

FIG. 14 is an elevational rear view of the exemplary base of FIG. 1 uncoupled with the facial brush of FIG. 1 in accordance with the present invention shown separately for clarity of illustration;

FIG. 15 is an elevational left side view of the exemplary base of FIG. 1 uncoupled with the facial brush of FIG. 1 in accordance with the present invention shown separately for clarity of illustration;

(Continued)

FIG. 16 is an elevational right side view of the exemplary base of FIG. 1 uncoupled with the facial brush of FIG. 1 in accordance with the present invention shown separately for clarity of illustration;

FIG. 17 is a downward-looking perspective view of the exemplary base of FIG. 1 uncoupled with the facial brush of FIG. 1 in accordance with the present invention shown separately for clarity of illustration;

FIG. 18 is a top plan view of the exemplary base of FIG. 1 uncoupled with the facial brush of FIG. 1 in accordance with the present invention shown separately for clarity of illustration; and,

FIG. 19 is a bottom plan view of the exemplary base of FIG. 1 uncoupled with the facial brush of FIG. 1 in accordance with the present invention shown separately for clarity of illustration.

The broken or dashed lines showing connection ports, buttons, or apertures of the facial brush with brush head cover, and the base which may be coupled thereto, depicts environment and/or components of the device that form no part of the claimed design.
